(57) **CLAIM**

The ornamental design for a vaping device, as shown and described.

DESCRIPTION

FIG. 1 is a perspective view of the vaping device; FIG. 2 is a right side elevational view of the vaping device; FIG. 3 is a left side elevational view of the vaping device; FIG. 4 is a front elevational view of the vaping device; FIG. 5 is a back elevational view of the vaping device; FIG. 6 is a top plan view of the vaping device; and, FIG. 7 is a bottom plan view of the vaping device. The broken lines in the drawings depict portions of the vaping device that form no part of the claimed design.
